C. E. MACDUFFEE.
MEANS FOR HOLDING AND CONVEYING AIR TUBES AND ELECTRIC CONDUCTORS TO
SUBMARINE DIVERS.
APPLICATION FILED DEC. 6, 1910.

989,532.

Patented Apr. 11, 1911.

UNITED STATES PATENT OFFICE.

CHESTER E. MACDUFFEE, OF NEW YORK, N. Y., ASSIGNOR OF ONE-FIFTH TO GEORGE A. TRAVER, OF BROOKLYN, NEW YORK, ONE-FIFTH TO JAMES P. REID, OF NEW YORK, N. Y., ONE-FIFTH TO JOHN L. GORDON, OF WEST HOBOKEN, NEW JERSEY, AND ONE-FIFTH TO ERNEST MEYER, OF TUXEDO, NEW YORK.

MEANS FOR HOLDING AND CONVEYING AIR-TUBES AND ELECTRIC CONDUCTORS TO SUBMARINE DIVERS.

989,532.

Specification of Letters Patent. Patented Apr. 11, 1911.

Application filed December 6, 1910. Serial No. 595,849.

To all whom it may concern:

Be it known that I, CHESTER E. MACDUFFEE, a citizen of the United States, residing at the borough of Manhattan, city, county, and 5 State of New York, have invented an Improvement in Means for Holding and Conveying Air-Tubes and Electric Conductors to Submarine Divers, of which the following is a specification.

10 In submarine diving where the air tubes and telephone or electric conductors are carried separately great difficulty arises while the diver is descending or ascending or while performing his duties among wreckage at 15 the bottom of a body of water in preventing tangling of the tubes or conductors, and the diver is often in great danger from such cause.

My invention relates to a means for holding 20 and conveying the air tubes and electric conductors to submarine diving armor in such a manner as to avoid such difficulty and danger, and consists of a single continuous and seamless tubing within which the air 25 tubes and electric conductors are contained and carried to the armor, to which the air tubes are connected by means of a peculiar attachment, permitting a free movement of the tubing at this point. This attachment 30 however, forms the subject matter of a separate co-pending application filed December 6, 1910, Serial No. 595,848.

In the accompanying drawing:—Figure 1 is an elevation of the upper part of an 35 armor for submarine divers, illustrating how my invention is applied to the same. Fig. 2 is an elevation in larger size and at right angles to Fig. 1 of a portion of the part shown in said figure. Fig. 3 is a section in 40 larger size at the dotted line x, x , Fig. 2, looking downward. Fig. 4 is a similar view at the dotted line y, y , of Fig. 2 looking upward, and Fig. 5 is a section at the dotted line z, z , of Fig. 3.

45 Similar reference numerals refer to like parts throughout the several views.

1 is a seamless tubing of any desired length, made up of two or more concentric 50 seamless tubes of rubberized canvas or other suitable material all vulcanized together. This tubing is preferably oblong in cross sec-

tion so as to present flattened opposite surfaces.

2 is an air-tight tubing of flexible character through which air is supplied to the 55 diver, and 3 is a similar tubing through which exhaled or vitiated air is conveyed from the armor and discharged into the atmosphere above water.

4 4 represent electric conductors for connection with a telephone in the helmet 5 of the armor 8 and 6 6 represent electric conductors for connection with an electric lamp or lamps contained in a casing 7 on the 60 armor.

9 represents a filling of insulating material, which forms a bed for the wires and thoroughly insulates them one from the other.

At or near the lower extremity of the tubing 1 the air tubes and electric conductors emerge therefrom in three branches, 10, 11 and 12. The branch 10 containing the electric conductors 4 4 and 6 6 is carried into the armor 8 through a suitable bushing 13; 75 the branch 11 representing the air supply tube 2 and the branch 12 the exhaust tube 3. These branches 11 and 12 are each provided at their outer ends with a screw-threaded coupling nut 14 which are to be screwed 80 upon the screw-threaded ends of tubular cylindrical members 15 projecting from a cylinder 16 attached to the armor 8. These tubular members 15 have a swinging movement which allows play to the air tubes 85 while the diver is descending or ascending or at work at the bottom, and prevents any undue strain upon the tubes at such times.

It will be readily understood that by my improved means of holding and carrying 90 the air tubes and electric conductors all danger or undue strain is avoided, and the flattened shape of the carrying tube facilitates the proper winding or unwinding of the same upon a reel, which I propose to employ 95 in its manipulation.

I claim as my invention:

1. The combination with a tubular holder of flexible material, of air supply and exhaust tubes interior thereof, electrical conductors also within said tubular holder and a filling of insulating material within said

tubular member into which said electrical conductors are embedded and insulated one from the other.

2. The combination with a tubular holder of flexible material having a branch of reduced diameter at or near one of its extremities, of air supply and exhaust tubes interior of the main body of said holder, electrical conductors also within said tubular holder and extending into and through said branch thereof, and a filling of insulating material throughout the main body of said holder into which said electrical conductors are embedded and insulated one from the other.
3. The combination with a tubular holder of flexible material, of air supply and exhaust tubes interior thereof throughout its length but separately emerging therefrom at or near one of its extremities, coupling nuts secured upon the outer ends of said air tubes, electrical conductors also within said tubular holder, and a filling of insulating material into which said electrical con-

ductors are embedded and insulated one from the other.

4. The combination with a tubular holder of flexible material having a branch of reduced diameter at or near one of its extremities, of air supply and exhaust tubes interior of the main body of said holder throughout its length but separately emerging therefrom at or near one of its extremities, coupling nuts secured upon the outer ends of said air tubes, electrical conductors also within said tubular holder and extending into and through said branch thereof, and a filling of insulating material throughout the main body of said tubular holder into which said electrical conductors are embedded and insulated one from the other.

Signed by me this first day of December 1910.

CHESTER E. MACDUFFEE.
